FLUID HEATER

Robert A. Foresman, Prospect Park, Pa., assignor
to Westinghouse Electric & Manufacturing
Company, East Pittsburgh, Pa., a corporation
of Pennsylvania

Application October 23, 1935, Serial No. 46,241

21 Claims. (Cl. 122—30)

My invention relates to fluid heaters of the type disclosed in my copending application, Serial No. 658,334, filed February 24, 1933, and it has for an object to provide improved apparatus of this kind.

A further object of my invention is to provide an improved heater for use with a fuel burning structure of the rotatable annular grate type, and having a magazine disposed therein for the 10 gravitational feed of fuel to the grate.

It is a further object of my invention to provide an improved heater of this type wherein a substantial portion of the weight of the fuel in the hopper is removed from the grate.

15 A still further object of my invention is to arrange, in a heater of this type, the access openings for the admission of fuel and for the removal of refuse on one side of the heater.

Still further objects of my invention are to provide an improved heating structure which may be manufactured in standardized sections for obtaining various sizes and ratings and which may be operated with a minimum of attention over long periods.

25 These and other objects are effected by my invention as will be apparent from the following description and claims taken in connection with the accompanying drawings, forming a part of this application, in which:

30 Fig. 1 is a front view of my improved heater, portions of which are shown in cross section, the intermediate portion of the heater and the grate supporting base thereof being shown in section and taken along the line I—I of Fig. 2 and the lower heater portion being in cross section and taken along the line A—A of Fig. 2;

Fig. 2 is a plan view of the apparatus shown in Fig. 1;

Fig. 3 is a sectional view taken along the line III—III of Fig. 1 and Fig. 5;

40 Fig. 4 is a sectional view taken along the line IV—IV of Fig. 1 with portions broken away for the sake of clearness, which portions are indicated by the offset line IV—IV of Fig. 5;

45 Fig. 5 is a developed view of the apparatus shown in the preceding views;

Fig. 6 is a developed view of a modified detail of Fig. 5; and,

50 Fig. 7 is a sectional view of a modified detail of the apparatus shown in Figs. 1 to 5, inclusive.

Reference will now be had to the drawings in which my improved fluid heater is generally indicated by the reference numeral 10 and which is supported on a base member 11. The latter includes inner and outer walls 12 and 13 upon which

an annular grate structure 14 is rotatably carried. The grate may be rotated in any suitable manner such as, for example, by a reciprocated pawl and ratchet mechanism 15, the driving means therefor being omitted as it forms no part 5 of the present invention.

The heater structure 10 preferably includes an upper and lower section 16 and 17 and an intermediate section 18 arranged in superimposed relation. I have disclosed but one intermediate 10 section 18 but it will be understood that a plurality of sections may be employed, the number of which is determined by the rating of the boiler or the amount of heat transfer surface necessary.

The heater 10 includes an outer wall 19 having 15 a space 21 formed therein for the medium to be heated, such as, for example, water. An inner wall or column 22 is disposed substantially in concentric relation with the outer wall 19 and includes a water space 23. The walls 19 and 22 20 are respectively carried by the walls 13 and 12 of the base 11 and are aligned, substantially, with the outer and inner circumferences of the annular grate 14.

Communication between the water spaces 21 25 of the various sections 16 to 18, inclusive, is provided by conduits 24, as the terminal portions of the wall 19 of each section is closed, as best shown in Fig. 1. This construction eliminates the necessity of large gaskets between the wall 19 of each section. The inner wall or column 22 of each section is open where it connects with the wall of an adjacent section, the open ends being provided with internal flanges 25 secured together by bolts 26. A gasket 27 may be employed for obtaining a fluid-tight connection between the flanges 25.

The heater 10 includes a plurality of circumferentially spaced wall members 28, 29, 31, and 32 which connect the inner and outer walls 22 40 and 19 and which are preferably provided with respective water spaces 33 to 36, inclusive. The water spaces 33 to 36 communicate with the spaces 21 and 23 as best shown in Figs. 3 and 4. The complementary portions of the walls 28, 29, 31, and 32 which are included in the various sections 16, 17, and 18 are clearly shown in the developed view (Fig. 5).

The circumferentially spaced walls 28 and 29 divide the annulus between the outer and inner 50 walls 19 and 22 into a pair of arcuate chambers 37 and 38, the first of which is a fuel receiving chamber or magazine and the latter of which is a combustion chamber. The lower end of the wall 28 terminates in spaced relation above the 55

- grate 14 for defining a fuel discharge orifice 39, through which fuel is carried into the combustion chamber 38 when the grate is rotated in a clockwise direction as viewed in Fig. 3, or in the 5 direction indicated by the dot and dash arrow of the developed view, Fig. 5. The depth of the fuel bed may be varied by an adjustable plate 41, movable in a vertical direction by adjusting nuts 42 and rod 43.
- 10 The upper or fuel supporting surface of the grate 14 may be inclined downwardly toward the outer periphery of the grate and the lower edge of the plate 41 disposed horizontally for providing a thicker bed of fuel adjacent the outer 15 periphery of the grate. The inclined grate, furthermore, facilitates the removal of ash therefrom and further reference to the removal of ash will be made hereinafter. I have found that, as the grate is rotated, the fuel tends to move inwardly of the grate, due to the friction between the fuel and the outer wall 19 of the combustion chamber. Therefore, with a fuel bed of initial 20 constant depth, the bed becomes progressively thinner at the outer periphery as the grate rotates and combustion becomes uneven, complete combustion of the fuel at the outer periphery of the grate being prior to the complete combustion of the fuel adjacent inner portions of the grate. I obviate this undesirable operation by 25 inclining the grate so that a fuel bed, which increases in depth from the inner to the outer portions of the grate, is admitted to the combustion chamber and, therefore, compensate for the movement of fuel inwardly of the grate.
- 30 Both walls 28 and 29 preferably connect with a top wall or drum 44, the water spaces 33 and 34 communicating with the interior of the drum 44. The wall 29 includes an offset portion 45 which is spaced above the grate and which extends toward the wall 28, whereby a floor is defined for a portion of the magazine 37. The offset portion 45 terminates in spaced relation with the wall 28 to define a passage 46 through which fuel passes to the grate. A wall portion 47 extends 35 downwardly from the end of the offset portion and terminates adjacent the grate 14. The wall portions 45 and 47 are preferably provided with water spaces 48 and 49 which communicate with the space 34 of wall 29. A false bottom 51 may be provided for the magazine 37, which bottom may be inclined toward the passage 46 at an angle equivalent to the angle of repose of the fuel.
- 40 It will be apparent from the foregoing description that a substantial portion of the weight of the fuel is carried by the bottom wall members 45 and 51 and that the grate 14 is relieved of this weight. Furthermore, the active fuel burning area of the grate is increased in an amount equivalent to the grate area lying beneath the bottom wall 45 and, as this wall is provided with spaces for water to be heated, the heat transfer surface of the heater is increased.
- 45 Fuel is admitted to the space 37 through an opening 52, preferably in the front of the heater, and closed by a door 53. For the convenience of the attendant, I locate the ash removal opening on the same side of the heater as the fuel opening 52 which openings are aligned substantially in a vertical plane. The ash removal opening is best shown at 54 in Fig. 4 and is formed in the outer wall 19 and beneath the bottom wall 45 of the magazine. Refuse of combustion may 50 be deflected outwardly of the grate toward the

opening 54 by one or more plates 55 secured to the heater structure in any suitable manner.

When a plurality of plates 55 is employed, they are spaced radially of the grate and are disposed at a tangent thereto as best shown in Fig. 4. 5 As the grate 14 is rotated, the ash carried thereby engages the plates 55 and is moved radially of the grate and passed through the opening 54 to an ash pit 56, from which the refuse may be removed through an access opening 57. As 10 stated heretofore, the fuel supporting surface of the grate 14 is inclined downwardly toward the outer periphery of the grate, which inclination facilitates the movement of ash radially of the 15 grate.

It may be desirable in some cases to provide 20 adjustments for the deflecting plates 55, so that the angle at which the plate rests with respect to the moving body of ash may be varied. Accordingly, I have shown the inner plate 55 provided with an adjusting screw 61, which may be rotated to swing the plate in a horizontal plane. The solid and the dot and dash lines in Fig. 5 show the inner plate 55 adjusted to different 25 positions. The inner end of the adjustable plate 55 is supported in any convenient manner to permit movement of the plate. In the embodiment disclosed, the plate 55 merely rests against the inner wall 22. The plate 55 may be firmly held in its adjusted position by a bolt 62.

A dust tight housing 58 is provided for the pit 56 in which the access opening 57 is formed. Preferably, containers 59, indicated by dot and dash lines in Fig. 4, are employed for collecting the ash as it passes through the opening 54, which 35 containers are removable from the housing 58 through the door 57. The ash pit 56 extends into the base 11 and is defined therein by radial walls 63 which divide the base 11 into arcuate chambers. One of these chambers is the pit 56 40 and the other chamber, indicated at 64, is a wind box disposed beneath the portion of the fuel bed within the combustion chamber 38. The walls 63 are aligned substantially with the magazine walls 28 and 29. (See Fig. 5.) As disclosed in 45 my copending application Serial Number 658,334, referred to heretofore, the wind box 64 may be divided into a plurality of chambers with respective dampers for regulating the flow of air to the 50 chambers.

The upper portion of the ash pit 56 is covered by a horizontal plate 65 upon which a thin layer of ash may collect and which cooperates with the grate structure to provide a seal for confining the passage of air from the wind box 64 to 55 the portion of the grate where combustion is effected. The grate structure 14 includes a plurality of radially-extending arms 66 which engage said layer of ash, as shown in Fig. 5, and prevent passage of air to the grate portions beneath the magazine 37 or the portion of the grate where the combustible is burned out.

The active portion of the grate which supports burning fuel lies substantially between the walls 28 and 29 within the arcuate combustion chamber 38. An arch 67, preferably provided with a water space 68, is disposed above the grate 14 and extends from the wall or baffle 32 to the magazine wall 29, the space 68 of the arch communicating with the water spaces 36 and 34. The 70 offtake for gases is indicated at 69 adjacent the top of the combustion chamber and a tortuous path for the flow of the gases above the arch 67 is provided by the walls or baffles 32 and 31. The latter baffle 31 terminates at its bottom in spaced 75

relation with the arch and is connected at its upper end to the drum or wall 44, the water space 35 being, preferably, in communication with the space within the drum. The path of the flow of gases through the combustion chamber is shown by arrows in Fig. 5.

The various walls of my improved heater may be formed in any suitable manner but are, preferably, of sheet metal welded together and reinforced by stay-bolts 11. Inspection and cleaning openings 71 and 72 are provided, respectively, in the outer and top walls 19 and 44, and are provided with suitable closures. The openings 71 and 72 are preferably formed, respectively, 15 by tubes 71a and 72a which traverse the water spaces and which are secured to the outer and inner members of the walls whereby further reinforcing of the walls is obtained and additional heat transfer surface provided.

20 Water to be heated or vaporized is admitted to the outer wall 19 of the lower section, as shown at 73. A portion of the entering water may be admitted to the intermediate section as shown at 74. Heated water or steam is removed from 25 the upper wall or drum 44 through one or more connections 75. A gauge glass 76 is provided for the heater when operating to produce steam, for viewing the water line which is maintained within the drum 44.

30 When in operation, the grate 14 is slowly rotated by the operating mechanism 15 and coal from the magazine 13 is advanced thereon into the combustion space 38, the depth of the fuel bed being determined by the elevation of the fuel leveling device 41. Air for combustion is delivered in any suitable manner to the wind box 64 and passes through the grate 14 to the fuel for promoting combustion thereof. The fuel is progressively burned as it advances through the combustion chamber 38, the thickness of the fuel decreasing and that of the ash increasing. The combustible is practically all burnt out of the coal by the time it passes beneath the wall member 29 so that only refuse remains. The latter is deflected from the grate 14 as heretofore described.

45 Excess air delivered to the combustion chamber 38 may be bled off, preferably to the stack, by means of a pipe 78 controlled by a damper 79. The pipe 78 may communicate with the combustion chamber 38 through the ash discharge opening 54 as shown. The amount of excess air delivered to the combustion chamber may, therefore, be controlled by regulating the by-pass dampers 79 so that the furnace is operated at 50 high efficiency. This means for regulating the amount of excess air delivered to the combustion chamber is disclosed and claimed in my copending application, Serial No. 26,600, filed June 24, 1935, and assigned to the Westinghouse Electric & Manufacturing Company.

60 Water to be heated enters the outer wall 19 of the section 17 and is heated or vaporized as it rises to the upper drum 44 through the inner chamber 23 and through the connecting conduits 24. The various walls and baffles and the arch being provided with water heating spaces present a large amount of heat transfer surface to the fire. It will be apparent that these surfaces, being for the most part vertical will not collect soot or dust 65 to any material degree.

70 In Fig. 7, I have shown a transverse section of a modification of my improved heater having a plurality of spaced arcuate wall members 81 arranged within the combustion chamber 38 for obtaining additional heat transfer surface. The

walls 81 are disposed substantially in concentric relation with the outer wall 19 and extend vertically within the combustion chamber 38. The walls 81 may intersect one or more of the circumferentially spaced walls or baffles 32 and 34 and are provided with spaces 82 for fluid to be heated, which spaces 82 are in communication with the spaces 35 and 36. The arcuate walls 81 are spaced from the outer and inner walls 19 and 22 and from each other to provide passages for the gases of combustion. As the walls 81 are vertically disposed, dust or soot will not gather thereon to any material degree and, therefore, their heat transferring qualities are substantially unimpaired with service.

15 I have shown in the first embodiment, an arch structure which is provided with water spaces and which forms a portion of the heat transfer surface of the boiler or heater 10. As shown in Fig. 6, an arch construction of refractories 83 is disclosed. 20 The refractories 83 may be disposed on angle members 84 secured to the inner and outer walls 19 and 22.

25 From the foregoing, it will be apparent that I have provided an improved fluid heater or boiler for a rotatable annular grate and having a fuel magazine arranged therein for the gravitational feed of fuel to the grate, which magazine is so arranged that a substantial portion of the weight of the fuel is removed from the grate. Furthermore, the arrangement of the magazine within the heater is such that the removal of refuse from the grate may be effected beneath the magazine, whereby the fuel admission opening to the magazine and the ash removal opening may be disposed on the same side of the heater structure.

30 By dividing the heater into sections which are superimposed, I am enabled to build relatively large boilers for steam heating service, which may be admitted through existing door openings of the 40 premises where the heater is to be installed. Various sizes and ratings may be obtained from a few standardized sections, as additional intermediate sections 18 may be employed where additional heat transfer surface is required. The 45 speed of the grate may be varied for different boiler ratings so that, with a few sizes of standardized sections, a relatively large number of heaters of various sizes and ratings may be economically produced.

50 While I have shown my invention in several forms, it will be obvious to those skilled in the art that it is not so limited, but is susceptible of various other changes and modifications without departing from the spirit thereof, and I desire, therefore, that only such limitations shall be placed 55 thereupon as are imposed by the prior art or as are specifically set forth in the appended claims.

55 What I claim is:

1. In fluid heating apparatus, the combination 60 of a rotatable annular grate, an outer wall having spaces therein for medium to be heated and arranged above the perimeter of the grate, first and second circumferentially spaced walls extending inwardly from the outer wall and joined 65 at their inner ends for defining a fuel magazine and a combustion chamber above arcuate portions of the grate; said first circumferentially spaced wall having a portion thereof spaced above the grate for defining, therewith, a fuel discharge orifice, said second circumferentially spaced wall terminating adjacent the grate, said circumferentially spaced walls having their bottom portions spaced apart a distance less than the distance separating the upper portions there- 75

of, whereby, the horizontal area of the magazine adjacent the grate is less than the horizontal area of the magazine remote from the grate; means for admitting fuel to the magazine and 5 means for rotating the grate.

2. The combination as claimed in claim 1 in which the fluid heater is formed of a plurality of complementary sections having means providing for the flow of fluid therebetween.

10 3. The combination as claimed in claim 1 having means for varying the depth of fuel delivered to the grate through said fuel discharge orifice.

4. The combination as claimed in claim 1 having means spaced from said first circumferentially spaced wall for deflecting refuse of combustion from the grate.

5. In fluid heating apparatus, the combination of a rotatable annular grate, an outer wall having spaces therein for medium to be heated and 20 arranged above the perimeter of the grate, first and second circumferentially spaced walls extending inwardly from the outer wall and joined at their inner ends for defining a fuel magazine and a combustion chamber above arcuate portions 25 of the grate; said first circumferentially spaced wall having a portion thereof spaced above the grate for defining, therewith, a fuel discharge orifice, said second circumferentially spaced wall terminating adjacent the grate, one 30 of said circumferentially spaced walls having an offset portion extending toward the other circumferentially spaced walls so that the portion of the fuel magazine adjacent the grate is of smaller horizontal area than the portion 35 thereof remote from the grate, means for admitting fuel to the magazine, and means for rotating the grate.

6. In fluid heating apparatus, the combination of a rotatable annular grate, an outer wall 40 having spaces therein for medium to be heated and arranged above the perimeter of the grate, first and second circumferentially spaced walls extending inwardly from the outer wall and joined at their inner ends for defining a fuel magazine and a combustion chamber above arcuate portions 45 of the grate; said first circumferentially spaced wall having a portion thereof spaced above the grate for defining, therewith, a fuel discharge orifice, one of said circumferentially spaced walls having an offset portion extending toward the other circumferentially-spaced wall 50 so that the portion of the fuel magazine adjacent the grate is of smaller horizontal area than the portion thereof remote from the grate, means 55 spaced circumferentially from the fuel discharge orifice for removing refuse from the grate, means for admitting fuel to the magazine, and means for rotating the grate.

7. In fluid heating apparatus, the combination 60 of a rotatable annular grate, an outer wall having spaces therein for medium to be heated and arranged above the perimeter of the grate, a magazine arranged for the gravitational feed of fuel to the grate and including a first wall extending inwardly from the outer wall and having its bottom portion spaced above the grate 65 for defining a fuel discharge orifice and a second wall extending inwardly from the outer wall and circumferentially spaced from the first wall, said first and second walls being connected at their inner ends, said second wall having a portion 70 thereof extending substantially in a horizontal plane and forming a bottom for a portion of the magazine; means associated with the second wall 75 for deflecting refuse from the grate, means for

admitting fuel to the magazine and means for rotating the grate.

8. The combination as claimed in claim 7 having a false bottom member arranged within the magazine above said horizontally extending portion of the second wall and at an angle thereto.

9. In fluid heating apparatus, the combination of a rotatable annular grate, an outer wall having spaces therein for medium to be heated and arranged above the perimeter of the grate, a 10 magazine arranged for the gravitational feed of fuel to the grate and including first and second circumferentially spaced walls extending inwardly from the outer wall and joined adjacent the central portion of the grate, said first circumferentially spaced wall having a portion thereof spaced above the grate for defining a fuel discharge orifice, said second circumferentially spaced wall including upper and lower portions 15 extending substantially in a vertical plane but circumferentially displaced with respect to each other and including a portion connecting the upper and lower portions for defining a bottom for a portion of the magazine, means for deflecting refuse from the grate beneath the horizontal 20 portion of the wall; means for admitting fuel to the magazine, and means for rotating the grate.

10. In fluid heating apparatus, the combination of a rotatable annular grate, an outer wall having spaces therein for medium to be heated 30 and arranged above the perimeter of the grate, a magazine arranged for the gravitational feed of fuel to the grate and including a first wall extending inwardly from the outer wall and having its bottom portion spaced above the grate 35 for defining a fuel discharge orifice and a second wall extending inwardly from the outer wall and circumferentially spaced from the first wall, said first and second walls being connected at their inner ends, said second wall having a lower portion 40 thereof extending toward said first wall for supporting a portion of the fuel in the magazine, means disposed beneath said portion of the second wall for deflecting refuse of combustion from the grate, means for admitting fuel to the magazine 45 and means for rotating the grate.

11. The combination as claimed in claim 10 having means for adjusting the refuse deflecting means with respect to the grate.

12. The combination as claimed in claim 10 50 wherein the refuse deflecting means includes a plurality of deflecting plates having their lower edges disposed adjacent the upper surface of the grate and radially spaced from each other, said plates being tangentially disposed with respect 55 to the grate.

13. In fluid heating apparatus, the combination of a rotatable annular grate, inner and outer walls arranged above inner and outer portions of the grate and enclosing respective spaces for 60 fluid to be heated, a fuel magazine arranged above an arcuate portion of the grate and including first and second walls connecting the inner and outer walls and having fluid spaces therein communicating with the spaces of the inner and 65 outer walls, said first magazine wall having a portion thereof spaced above the grate for defining an orifice for the passage of fuel there-through, means for varying the depth of the fuel bed passed through the orifice, said second 70 magazine wall terminating adjacent the grate and having a portion thereof extending toward the first magazine wall for supporting a portion of the fuel in the magazine, a plurality of deflecting devices arranged beneath said portion 75

of the second magazine wall for moving refuse of combustion from the grate, means associated with at least one of said devices for adjusting the angularity thereof with respect to the grate, 5 means for admitting fuel to the magazine, and means for rotating the grate.

14. In fluid heating apparatus, the combination of a rotatable annular grate, a wall member forming a portion of the heat transfer surface 10 of the fluid heater and arranged above the perimeter of the grate, a fuel magazine disposed above an arcuate portion of the grate for the gravitational feed of fuel thereto and including first and second walls circumferentially spaced from 15 each other and extending inwardly from said wall member, said first magazine wall terminating in spaced relation above the grate for defining a fuel discharge orifice, said second magazine wall having a portion thereof extending toward 20 the first magazine wall for supporting a portion of the fuel in the magazine, means arranged below said portion of the second magazine wall for removing refuse of combustion from the grate, said last-mentioned means including a 25 passage through which refuse is discharged and a deflecting device extending across the grate for moving refuse toward said passage as the grate is rotated, means for admitting fuel to the magazine, and means for rotating the grate.

15. The combination as claimed in claim 14 in which said fuel admission means includes an opening through which fuel is deposited in the magazine and which is alined, substantially, in a vertical plane above said refuse discharge passage.

16. In fluid heating apparatus, the combination of a rotatable annular grate, an outer wall having spaces therein for medium to be heated and arranged above the perimeter of the grate, 40 a magazine arranged for the gravitational feed of fuel to the grate and including first and second circumferentially spaced walls, extending inwardly from said outer wall and joined at their inner ends and including a bottom wall spaced above the grate and connected to one of said circumferentially spaced walls, said bottom wall extending across a portion of the magazine toward the other of said circumferentially spaced walls, whereby a support for a portion of the fuel in said magazine is defined, one of said magazine walls terminating above the grate in spaced relation for defining an orifice through which fuel is passed as the grate is rotated, means spaced from said orifice for deflecting refuse from the grate, means for admitting fuel to the magazine, and means for rotating the grate.

17. In fluid heating apparatus, the combination of a rotatable annular grate, inner and outer walls arranged above the inner and outer peripheries of the grate for defining a combustion chamber above the grate said inner and outer walls enclosing respective spaces for fluid to be heated, a radially extending wall connecting the inner and outer walls and having a space therein communicating with the spaces enclosed by the inner and outer walls, and an arcuate wall disposed within the combustion chamber intermediate of the inner and outer walls and having a space formed therein for fluid to be heated,

said arcuate wall intersecting the radially extending wall and having its fluid space communicating with the space of the radially extending wall.

18. In fluid heating apparatus, the combination of a rotatable annular grate, inner and outer walls arranged above the inner and outer peripheries of the grate for defining a combustion chamber above the grate, said inner and outer walls enclosing spaces for fluid to be heated, a 10 radially-extending wall connecting the inner and outer walls and having a space therein communicating with the spaces enclosed by the inner and outer walls, and an arcuate wall disposed within the combustion chamber intermediate of 15 the inner and outer walls and having a space formed therein for fluid to be heated, said fluid space of the arcuate wall being in communication with the fluid spaces of said inner and outer walls and of said radially-extending wall. 20

19. In fluid heating apparatus, the combination of a rotatable annular grate, a boiler structure disposed above the grate and including inner and outer water wall members arranged above the inner and outer peripheries of the grate, 25 respectively, and defining an annular space thereabove, radially extending water walls connecting the inner and outer walls for dividing said space into a fuel chamber and a combustion chamber, means for rotating the grate so 30 that fuel is carried thereby from the fuel chamber to the combustion chamber, and means including one of said radially extending walls for levelling the fuel carried into the combustion chamber by the grate, said grate having its fuel supporting surface sloped downwardly from the inner to the outer periphery thereof, whereby the thickness of the bed of fuel carried by the grate into the combustion chamber increases progressively from the inner to the outer peripheries of the grate. 35

20. In fluid heating apparatus, the combination of a rotatable circular grate, a structure having spaces therein for fluid to be heated and defining a combustion chamber above a segment of the grate, and a magazine for fuel disposed above a second segment of the grate and beside a portion of the combustion chamber, said structure including a substantially horizontal wall member disposed below the magazine and having a space 40 therein for fluid to be heated and an opening 45 for levelling the fuel carried into the combustion chamber by the grate, said grate having its fuel supporting surface sloped downwardly from the inner to the outer periphery thereof, whereby the thickness of the bed of fuel carried by the grate into the combustion chamber increases progressively from the inner to the outer peripheries of the grate. 50

21. In a fluid heating apparatus, the combination of a rotatable circular grate, a fluid heating structure associated with the grate and having a space formed therein for fluid to be heated, 55 said structure defining a combustion chamber above a segment of the grate, a magazine for fuel disposed beside a portion of the combustion chamber for delivering fuel by gravity to a second segment of the grate, a substantially horizontal wall member having a fluid space therein arranged below said magazine and including an opening for the passage of fuel from 60 the magazine to the grate, and fluid cooled means extending transversely of the grate for defining said first and second segments of the grate. 65

ROBERT A. FORESMAN.
